UNITED STATES PATENT OFFICE.

JAMES A. BROWN, OF CEDAR RAPIDS, IOWA, ASSIGNOR TO PERFECTION GAS ENGINE COMPANY, OF CEDAR RAPIDS, IOWA, A CORPORATION OF SOUTH DAKOTA.

EXHAUST-VALVE-ACTUATING MEANS FOR INTERNAL-COMBUSTION ENGINES.

1,261,355.

Specification of Letters Patent.

Patented Apr. 2, 1918.

Application filed March 8, 1917. Serial No. 153,499.

To all whom it may concern:

Be it known that I, JAMES A. BROWN, a citizen of the United States of America, and a resident of Cedar Rapids, Linn county,

5 Iowa, have invented certain new and useful Improvements in Exhaust-Valve-Actuating Means for Internal-Combustion Engines, of which the following is a specification.

My invention relates to improvements in 10 exhaust-valve actuating means for internal combustion engines wherein said valve actuating means is operated alone by employing a portion of the exhausted gases arising from combustion of the fuel consumed in the 15 combustion chamber of an engine, and the object of my improvement is to automatically control the action of said valve-actuating device by means of suitable connecting mechanism between said device and the 20 speed regulating device of the engine.

This object I have accomplished by the means which are hereinafter described and claimed, and which are illustrated in the accompanying drawings, in which Figure 1 25 is a side elevation, in partial section, of an internal combustion engine supplied with my improved exhaust-valve actuating means and with my mechanism for controlling the latter automatically, with parts broken 30 away; Fig. 2 is a detail plan view of the connecting mechanism between the engine governor and the tripping or releasing elements of the exhaust-valve actuating means, with parts broken or sectioned 35 away, and Fig. 3 is a detail enlarged elevation, taken at an angle of 90 degrees to the view shown in said Fig. 1, of said tripping or releasing mechanism for the exhaust-valve. Fig. 4 is a perspective view of the 40 same mechanism.

Similar numerals of reference denote corresponding parts throughout the several views.

I have shown my improved exhaust-valve 45 actuating-means and the governing mechanism for the latter as employed in combination with a well-known type of horizontal stationary engine mounted on a fixed support 35, but it is obvious that said mechanism may be used on any other type of internal combustion engine without departing from the principle of my invention.

The engine cylinder 5 contains the usual reciprocal piston 6 having a pitman pivotally connected between it and the crank-

pin of a crank-shaft 29 rotatably mounted in bearings (not shown) on the frame 35, and which may have thereon the usual fly-wheel, not shown.

The numeral 1 denotes a vertically disposed auxiliary cylinder mounted on the cylinder-head of said engine, and having in its upper removable head an inlet-port 2 in communication by means of a conduit 3, with an auxiliary exhaust-port 4 in the engine-cylinder 5. The cylinder 1 has divisional partitions 20 and 34, of which the former is provided with a centrally located seat for the exhaust-valve 21 spaced from the lower head 11, and the latter with a 70 central orifice through which the stem 8 of said valve extends upwardly into a chamber 36 containing a reciprocating piston 7 above the upper end of said stem. Within the chamber 36 and under said piston 7, a standard 12 projects upwardly fixedly from the partition 34. This standard has a pair of spaced lateral lugs 15 between which is medially pivotally mounted an oscillatory lever 13 having a detent 26 at its upper end. 75

The numeral 9 denotes a fixed arm on the upper part of the valve stem 8, having an acutely angled upper edge to fit under the hooked detent 26 on the lever 13, and a coiled compression-spring 10 encircles said 80 stem, and is adapted to normally propel said stem 8 upwardly to keep the exhaust-valve 21 closed against its seat.

The numeral 16 denotes a bell-crank lever medially pivoted upon the partition 34 and 90 having one end normally in engagement with a beveled part 25 of the lower end of the lever 13 to hold the latter upright fixedly.

A standard 27 extends upwardly from the 95 partition 34 and carries at its upper end a lateral plate-spring 28 whose free end engages the arm 9 and is adapted to retain the latter yieldingly in its seat when engaged with the detent 26 of the oscillatory lever 13. 100 The lower part of said lever is beveled away at the back to permit it to rock freely when released by the engaging device now to be described.

Referring to Figs. 2 and 4, a bell-crank 105 lever 16 is mounted to rock on a pivot-stud on the partition 34, and has one end formed to engage the beveled off angle 25 of the lower end of said lever 13, and is held in yielding engagement therewith by a spring 17 mount- 110

ed on said pivot-stud and which engages the opposite end of said bell-crank lever.

On the crank-shaft 29 is fixed a sleeve 31 on which is mounted a slidable rotatable 5 terminally-flanged spool 30. Said sleeve has oppositely-directed pairs of fixed arms 32 between which are pivoted a pair of governor-weights 33 having fingers inturned to pass movably between the flanges of said 10 spool. A lever 18 is medially pivoted between lugs 19 on the engine-casing, and has one end positioned movably between the flanges of said spool. Its other end is bent and passed through an opening 37 in the 15 cylinder 1 and engages with the outer end of the bell-crank lever 16.

A chamber 38 in the cylinder 1 below the partition 20 opens by means of a relatively large port into the combustion chamber of 20 the cylinder 5. On the lower face of the relatively large exhaust-valve 21 is an eccentric stud 22. On the adjacent face of the engine-piston 6 is a tappet-pin 23 in line with the stud 22.

25 Operation:

The exhaust-valve 21 being closed against its seat, the auxiliary piston 7 in its uppermost position, and the engine piston 6 having receded on its power-stroke to uncover 30 the auxiliary exhaust-port 4, a portion of the burnt gases of combustion rush through said port, the conduit 3, and the port 2 into the chamber 36 of the cylinder 1, forcing down the piston 7, which in turn, pushes down the 35 stem 8 against the tension of the spring 10 and forces open the exhaust-valve 21. The fixed arm 9 on said valve-stem moves down along the upper end of the trigger 13, and is caused by the pressure of the spring 28 to 40 pass into the notch thereon and become interlocked with the detent 26 thereon to hold the exhaust-valve open.

When the engine piston 6 returns, the tappet pin 23 thereon passes through the 45 opening in the cylinder-head, engages with the eccentric pin 22 on the exhaust-valve 21 and rocks said valve and its stem enough to disengage the arm 9 from the hooked detent 26 of the lever 13, the spring 10 yielding 50 downwardly and torsionally as the bevel of the arm slides over the bevel of the detent, thus permitting the spring 10 to push said stem 8 and the piston 7 upwardly to their former positions, closing the exhaust-valve 55 21. The lever 13 is held from swinging by the lever 16 during this operation, the bent-over end of the arm 18 contacting with and normally locking the said lever 16 against the tension of the spring 17. The above-described sequence of operations proceeds automatically without change while the engine is running at normal speed, the bell-crank lever 16 holding the lever 13 upright. In 60 case the speed of the engine should increase

beyond a predetermined limit, the outward 65 movements of the governor weights 33 cause their detents to press upon the spool flange 30 sliding it on the sleeve 31 to rock the lever 18, thereby causing the bent-over end of the latter to move away from the 70 bell-crank lever 16, releasing the latter so that it can rock freely on its pivot and be kept in contact with the lever 13 which may swing freely to and fro, and the acutely-angled arm 9 cannot become disengaged 75 while so swinging from under the hooked detent 26 being held therein by the spring 28, whereby the exhaust-valve 21 is held open until the speed of the engine has been reduced to the normal.

By the above means, the action of the exhaust valve actuating means is automatically regulated. The lever 18 may be used in connection with any other form of governor mechanism desired, and the connections 85 between the governor and said oscillatory lever 13 may also be varied in their elements, their forms, or proportions, without departing from my invention.

It will be seen that by the use of my device, a very large exhaust-valve and exhaust 90 passages may be employed whereby the combustion chamber may be quickly scavenged, thus instantaneously and completely releasing the heated gases resulting from combustion of the fuel, which keeps down the temperature in the combustion chamber, and also saves power which might otherwise be lost on the return stroke of the piston because of compression of gases not otherwise 95 completely driven out of the combustion-chamber.

Having described my invention, what I claim as new, and desire to secure by Letters Patent, is:

1. In an internal combustion engine, in combination, mechanism actuated solely by pressure of a portion of the exhaust gases for opening the main exhaust-valve, including a separable locking-device containing a 110 swinging element adapted to hold the exhaust-valve open and yieldable resilient means to hold said element locked while permitting it to swing freely, means operable by the engine at a certain point in the cycle thereof 115 to unlock said locking-device, a resilient connection adapted to return said exhaust-valve when unlocked to its closed position, a speed-governor actuated by the engine, and a lever rocked by said speed-governor into 120 or out of engagement with said swinging element, retaining the latter when engaged therewith in one position against the tension of said yieldable resilient means to permit said engine-operated means to unlock 125 said locking-device releasing the exhaust-valve to be closed by said resilient-connection.

2. In an internal combustion engine, in combination, mechanism actuated solely by pressure of a portion of the exhaust gases for opening the main exhaust-valve, including a separable locking-device containing a swinging element adapted to hold the exhaust-valve open and yieldable resilient means to hold said element locked while permitting it to swing freely, means oper-
5 able by the engine at a certain point in the cycle thereof to unlock said locking-device, a resilient connection adapted to return said
10 exhaust-valve when unlocked to its closed position, and means movable into or out of engagement with said swinging element, re-
taining the latter when engaged therewith against the tension of said yieldable resilient means to permit said engine-operated means only at that time to unlock said locking-de-
vice releasing the exhaust-valve to be closed 20 by said resilient connection.

Signed at Cedar Rapids, Ia., this 2d day
of March, 1917.

JAMES A. BROWN.
